DESIGN FOR A DRESS

Ben Sheinbaum, New York, N. Y.

Application July 27, 1944, Serial No. 114,593

Term of patent 7 years

(Cl. D3—26)

To all whom it may concern:

Be it known that I, Ben Sheinbaum, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific pocket and trim, arranged on the upper waist portion of the dress disclosed.

I claim:

The ornamental design for a dress, substantially as shown and described.

BEN SHEINBAUM.
